VISE HAVING SLIDABLE AND TURRET JAWS

Ladimer Patrick, Kettering, Ohio

Application June 20, 1957, Serial No. 666,882

5 Claims. (Cl. 81—20)

This invention is directed to a vise, and particularly to a vise which is easily and efficiently manufactured from parts which are made, for the most part, from bar stock and castings of a simple nature, thus to provide a vise of high quality and of low cost.

An object of this invention is to provide a vise with a rotatable turret jaw, in which the jaw is held by a bolt construction allowing the tightness of the bolt to be easily adjusted to secure the desired turning ease of the turret jaw.

Another object of this invention is to provide a vise in which a turret jaw and a longitudinally movable jaw are mounted on a straight rectangularly sided bar, which bar is held on the base by two bolts which additionally serve to secure the turret jaw and a stationary screw post on the vise.

Another object of this invention is to provide a vise having a longitudinal base with a transverse cross section for part of its length in the form of an inverted T and another part of its cross section in the form of a U, the surfaces of these two parts of the base being in the same horizontal plane and holding a flat rectangular bar on said surfaces, the construction being such that a turret jaw may be rotationally mounted on the U part of the base and the longitudinally movable jaw and stationary post therefor may be positioned above the inverted T part of the base in such a manner that the movable jaw may slide on the bar, and may have a flanged engagement therewith along its edges, and the turret jaw may be mounted to rotate freely above the bar by means of a single bolt which also secures the bar to the base, the post also being held by a single bolt which holds the post to the bar and the bar to the base.

Another object of this invention is to provide a vise having a turret jaw with a plurality of sides in which at least one of the sides has a V-shaped groove with a longitudinal cut to enable the sides of the groove to be machined to a smooth finish.

Further objects of this invention will become apparent as the description proceeds with reference to the accompanying drawings, in which:

Figure 1 is a top plan view of the vise.

Figure 2 is a vertical, longitudinal cross section taken along the line 2—2 of Figure 1.

Figure 3 is a transverse, vertical cross section taken along the line 3—3 of Figure 2.

Figure 4 is an exploded view of the vise, in perspective.

A vise, according to this invention, includes a longitudinal base 10, which has a transverse cross section in the form of an inverted T for part of its length, from shoulders 11 to a main end wall 12. Another part of the length of the base 10 is in the form of a U, such part extending from the shoulders 11 to a main end wall 13. The base 10 also has slotted extensions 14 and 15 to receive bolts for securing the vise to a bench, or the like.

A bottom 19 of the inner surface of the U portion of the base 10, and a top portion 20 of the inverted T are

2

in the same horizontal plane. A horizontal, flat, rectangularly cross-sectioned bar 22 rests on the flat continuous surfaces 19 and 20 of the base. The width of the bar 22, indicated at an edge 23, is slightly smaller than the width of the bottom 19 of the U-shaped portion 19, as indicated at an edge 24, the bar fitting snugly within the upwardly directed branches 25 and 26 of the U-shaped portion of the base. The width of the bar 22 is greater than the width 28 of the top portion 20 of the inverted T of the base, so the bar 22 has outwardly extending edges 30 beyond sides 31 of the top surface of the inverted T, as indicated in Figure 3.

The height of the bar 22, as indicated by an edge 33, is slightly lower than the height of the shoulders 25 and 26 of the U-shaped portion of the base, so the top surfaces 34 and 35 of such shoulders are slightly higher than the top surface 36 of the bar 22. The surfaces 34 and 35 thus provide a sliding surface support for a flat turret jaw 60 hereinafter to be more fully described. A predetermined clearance 22a is provided between the bar 22 and the bottom of the turret jaw 60.

A stationary vertical post 40 is secured on one portion of the bar 22 which rests on the surface 20 of the base 10. The post 40 has a horizontal tapped opening 41 extending longitudinally of the vise, to receive a longitudinal screw 42 for turning movement therein. A longitudinally movable jaw 45 rests on this portion of the bar 22 with downwardly and inwardly extending flanges 46 and 47 (Fig. 3) surrounding the outwardly extending edges 30 of the bar 22. The construction is such that the jaw 45 may move longitudinally on the bar 22, but cannot be substantially lifted from such bar.

The screw 42 has one end 50 secured to the movable jaw by being rotationally inserted in an untapped opening 51 in the jaw 45, and by being provided with a groove 52 for the reception of the pin 53, which produces a thrust bearing between the jaw 45 and the screw 42. The pin 53 is slightly shorter than a hole 53a within which it is tightly fitted and from which it may be knocked out to remove the screw 42 from the jaw 45. A nurled knob 59, or other form of handle, forms means for turning the screw 42.

The stationary post 40 is secured to the bar 22, and the bar 22 is secured to the base 10, at one end, by means of the upwardly directed bolt 54, having a head 55 bearing upwardly toward the bottom of the base 10, and passing loosely through openings 56 and 57 respectively in the base 10 and bar 22, and threadedly engaging a vertical tapped hole 58 in the post 40 to secure the post 40 to the bar 22, and one end of the bar 22 to the T portion of the base 10.

The flat turret jaw 60, of square horizontal cross section, or other polygonal cross section, is rotationally mounted above one end portion of the bar 22 by a downwardly directed bolt 61 having a head 62 downwardly bearing toward the flat jaw 60, and preferably against an annular shoulder 63 within the flat jaw 60, which is formed by the change in diameter of openings 64 and 65. The head 62 is provided with a hexagonal wrench opening 66 for the reception of an Allen wrench, or the like, to be used as hereinafter described. The bolt 61 passes loosely the vertical holes 64 and 65 in the jaw 60 and a vertical hole 68 in the base 10. The bolt 61 threadedly engages a tapped hole 69 in the flat bar 22. A jam nut 70 is placed over the end 71 of the bolt 61 which securely holds the bar 22 downwardly on the base 10 by reason of the upward bearing action of the jam nut 70 toward the bottom of the base 10. The closeness or looseness of the jaw 60 with relation to the top surfaces 34 and 35 of the U portion of the base 10 is regulated by turning the bolt 61 with an Allen wrench inserted in the hole 66, and by

turning the bolt to obtain the desired holding action on the jaw 60 for easy loose turning thereof. Thereafter the jam nut 70 is tightened to produce a pulling action between the bottom of the base 10 and the bar 22. Proper manipulation of the Allen wrench and a wrench on the nut 70 produces the desired clearance between the lower surface of turret jaw 60 and the top U surfaces 34 and 35.

The jaws 45 and 60 are adapted to receive and hold a plurality of differently shaped pieces between them. To this end, the jaw 45 is provided with a large, flat vertical face 80 and a horizontal step of groove 81 near the top. Also a vertical V-shaped groove 82 is placed near the center of the jaw 45. The turret jaw 60 preferably has upper and lower parallel faces. One of the sides of jaw 60 has a horizontal groove 85 adapted to hold cylindrical rods or tubes against the flat face 80 of the movable jaw 45. Another face of the jaw 60 has a small vertical V-shaped groove 86 adapted to hold relatively small cylindrical or otherwise shaped rods in vertical position in cooperation with the vertical groove 82 heretofore described. Another face of the jaw 60 has a relatively large vertical groove 88 adapted to hold in vertical position cylindrical or otherwise shaped articles in cooperation with the vertical groove 82 of jaw 45. Another face of the jaw 60 has a large flat face 89 adapted to hold flat pieces, wedge-shaped pieces, or otherwise shaped pieces between the faces 89 and 80. A V-shaped groove 90 is placed at the upper end of the groove 86, to hold discs, or the like, in horizontal position in cooperation with the groove 81 on the jaw 45. In a similar manner, a V-shaped groove or step 91 is placed above the vertical groove 88 and is likewise adapted to hold discs or the like of larger dimension in cooperation with the groove 81 of jaw 45. A horizontal groove or step 92, above the flat face 89 is adapted to hold flat pieces in cooperation with the groove 81 of jaw 45.

Small vertical central grooves 93 and 94 are placed at the apexes of the V-shaped grooves 86 and 88 to permit the faces of these grooves to be machined to a smooth finish. A similar groove 97 is made at the apex of the V-shaped groove 85 to permit machining of these surfaces.

If desired, a depression 100 is placed on the upper surface of the jaw 60 for the placing of the name of the manufacturer or the purchaser. Also the bottom of the base 10 may be provided with circular, oblong, or rectangular cut outs 101, 102 and 103 to lighten the weight of the base 10.

Many of the parts used to manufacture the vise may be purchased as stock pieces, or may be cut from stock bars, or the like. For example, the screw 42 may be cut from long, threaded bar stock. The bar 22 and the part 40 likewise may be cut from long stock bars. The base 10 may be cast and roughly machined, and only the surface 19 and 20 need be treated in this manner. The rotatable jaw 60 may be made from bar stock of slightly larger dimension than the finished product or may be cast and then roughly machined to final shape, after which it may be case hardened and machined to final dimension.

The entire vise can be assembled and held together by the two bolts 54 and 61. The movable jaw 45 rides smoothly on the bar 22. The correct looseness of turning movement of the jaw 60 may be calibrated by turning the bolt 61 in relation to the bar 22 so that the proper clearance is provided between the jaw 60 and the faces 34 and 35. Thereafter the jam nut 70 is tightened without materially affecting the calibration of the jaw 60 with respect to its turning movement.

Thus it is to be seen that I have provided a very efficient turret vise which can be manufactured at a very low price.

While the preferred form of the invention has been disclosed, as required by statute, other forms may be used, in accordance with the scope of the claims which follow.

I claim:

1. A vise comprising: a longitudinal base having a transverse cross section for part of its length in the form of an inverted T, and a transverse cross section for another part of its length in the form of a U, the bottom inner surface of the U being wider than the top surface of the inverted T, and being in the same horizontal plane; a horizontal, flat, rectangular cross-sectioned bar having a width slightly less than the width of the inner surface of said U and a height slightly less than the inner height of said U, and having a first portion of its length positioned and secured within said U, and having a second portion of its length resting on, secured on, and having outwardly extending edges beyond the sides of, the top surface of said inverted T; a stationary vertical post secured on said second portion of said bar and having a horizontal tapped opening extending longitudinally of said vise; a longitudinally movable jaw resting on said second portion of said bar with downwardly and inwardly extending flanges surrounding said outwardly extending edges of said bar; a longitudinal screw having one end longitudinally secured to said movable jaw by a thrust bearing, said screw threadedly engaging said tapped opening of said vertical post and having turning means at its other end; and a polygonally horizontal-cross-sectioned flat jaw rotatably mounted above said first portion of said bar upon a fixed vertical axis.

2. A vise comprising: a longitudinal base having a transverse cross section for part of its length in the form of an inverted T, and a transverse cross section for another part of its length in the form of a U, the bottom inner surface of the U being wider than the top surface of the inverted T and being in the same horizontal plane; a horizontal, flat, rectangular cross-sectioned bar having a width slightly less than the width of the inner surface of said U and having a first portion of its length positioned within said U and having a second portion of its length resting on, and having outwardly extending edges beyond the sides of, the top surface of said inverted T; a stationary vertical post on said second portion of said bar and having a horizontal tapped opening extending longitudinally of said vise; an upwardly directed vertical bolt having a head bearing upwardly toward the bottom of said base, passing loosely through openings in said base and bar, and threadedly engaging a vertical tapped hole in said post to secure said post to said bar and one end of said bar to the T part of said base; a longitudinally movable jaw resting on said second portion of said bar with downwardly and inwardly extending flanges surrounding said outwardly extending edges of said bar; a longitudinal screw having one end rotationally secured to said movable jaw by a thrust bearing, said screw threadedly engaging said horizontal tapped opening of said vertical post and having means for turning said screw at its other end; a polygonally horizontal-cross-sectioned flat jaw rotationally mounted above said first portion of said bar; a downwardly directed vertical bolt having a head downwardly bearing toward said flat jaw, passing loosely through a vertical hole in said flat jaw, threadedly engaging a tapped hole in said flat bar, rotationally to hold said flat jaw above said bar, and passing loosely through a vertical hole in said base; and a jam nut threadedly engaging the end of said last-named bolt and having an upward bearing toward the bottom of said base to hold the other end of said bar within the U part of said base.

3. A vise comprising: a longitudinal base having a transverse cross section for at least a part of its length in the form of an inverted T; a horizontal, flat, rectangular cross-sectioned bar having a width greater than the top of said inverted T and resting thereon with outwardly extending edges beyond the sides of said top of said inverted T; a stationary vertical post near a first end of said bar and having a horizontal tapped opening extending longitudinally of said vise; an upwardly directed vertical bolt having a head bearing upwardly toward the

bottom of said base, passing loosely through openings in said base and bar, and threadedly engaging a vertical tapped hole in said post to secure said post to said bar and said first end of said bar to said base; a longitudinally movable jaw resting intermediate the ends of said bar with downwardly and inwardly extending flanges surrounding said outwardly extending edges of said bar; a longitudinal screw having one end rotationally secured to said movable jaw by a thrust bearing, said screw threadedly engaging said horizontal tapped opening of said vertical post and having turning means at its other end; a polygonally horizontal-cross-sectioned flat jaw rotationally mounted above a second end of said bar; a downwardly directed vertical bolt having a head downwardly bearing toward said flat jaw, passing loosely through a vertical hole in said flat jaw, threadedly engaging a tapped hole in said flat bar, rotationally to hold a predetermined clearance between said flat jaw and said bar, and passing loosely through a vertical hole in said base; and a jam nut threadedly engaging the end of said last-named bolt and having an upward bearing toward the bottom of said base to hold said second end of said bar on said base.

4. A vise comprising: a horizontal base having a transverse cross section for at least a part of its length in the form of an inverted T; a horizontal, flat bar having a rectangular cross section for at least a part of its length with a width greater than the top of said inverted T and resting thereon with outwardly extending edges beyond the sides of said top of said inverted T; a stationary vertical post secured near a first end of said bar and having a horizontal tapped opening extending longitudinally of said vise; means to secure said post to said bar and said bar to said base; a longitudinally movable jaw resting intermediate the ends of said bar with downwardly and inwardly extending flanges surrounding said outwardly extending edges of said bar; a longitudinal screw having one end rotationally secured to said movable jaw by a thrust bearing; said screw threadedly engaging said horizontal tapped opening of said vertical post and having turning means at its other end; a polygonally horizontal-

cross-sectioned flat jaw rotationally mounted on a second end of said bar; a downwardly directed vertical bolt having a head downwardly bearing toward said flat jaw, passing loosely through a vertical hole in said flat jaw, and threadedly engaging a tapped hole in said flat bar, rotationally to hold a predetermined clearance between said flat jaw and said bar; and means to lock said bolt in position on said base.

5. A vise comprising: a longitudinal base having a raised flat ridge for at least a part of its length; a horizontal, flat, bar having straight uniform rectangular sides for at least a part of its length with a width greater than the top of said flat ridge and resting thereon with outwardly extending edges beyond the sides of said flat ridge; a stationary vertical post near a first end of said bar and having a horizontal tapped opening extending longitudinally of said vise; means to secure said post to said bar and said bar to said base; a longitudinally movable jaw resting intermediate the ends of said bar with downwardly and inwardly extending flanges surrounding said outwardly extending edges of said bar; a longitudinal screw having one end rotationally secured to said movable jaw by a thrust bearing, said screw threadedly engaging said horizontal tapped opening of said vertical post and having turning means at its other end; a flat jaw mounted above a second end of said bar; a downwardly directed vertical bolt having a head downwardly bearing toward said flat jaw, passing loosely through a vertical hole in said flat jaw, and threadedly engaging a tapped hole in said flat bar, to hold said flat jaw and said bar; and means to lock said bolt in position on said base.
